SHOE MACHINE

Filed July 22, 1927

INVENTOR.
Thomas Lund
By his Attorney
Nelson M. Howard

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

SHOE MACHINE.

Application filed July 22, 1927. Serial No. 207,698.

This invention relates to machines for making shoes and particularly to such machines employed for the insertion of fastenings, as in the attachment of heels. In machines of this character and in others in which work of varying thickness is clamped for the driving of the fastenings, it is a common practice to first apply a preliminary or measuring pressure, which establishes proper contact of the engaging members with the work. Then a further relative movement of the members creates a final or clamping pressure. A measuring mechanism in such machines, of which an excellent example is disclosed in Letters Patent of the United States No. 1,157,688, Glidden, October 26, 1915, may include movable wedges restrained by guides secured in place by screws and subjected to considerable strain in operation.

An object of my invention is to provide for more effective retention, in such mechanisms as above indicated, of the guiding or other fixed members, with a resulting reduction in the wear of and the liability of damage by loosened parts. This I accomplish by associating with the guide means engaging its ends and being variable as to the pressure exerted. Thus the guide is held firmly against longitudinal displacement, and the loosening effect upon the other securing means for the guide is minimized. The retaining or pressure means is preferably in the form of an abutment-lever and, in such an organization as that of the above patent, contacts with a bar furnishing a guide for one of a series of co-operating wedges.

A further object of the invention is to support securely, with the use of few elements, a casing for enclosing such a mechanism as that which measures the work in the machine disclosed in the previously mentioned patent. To this end, one element is caused to perform two functions—to serve as a mounting both for the casing and for the retaining or abutment means for a fixed member enclosed by the casing, as the guide member of measuring mechanism. As herein illustrated, there is threaded into the machine-frame, at each extremity of the guide member, a screw, upon which the casing for the mechanism is supported, and these screws also carry the levers or other abutment members which contact

with the guide member. Regardless of the manner in which the abutment means is arranged, I prefer to support the casing upon a plurality of fixed members and upon an additional adjustable member, this last element being illustrated as in the form of an eccentric. By this arrangement, simultaneous contact is obtained at such a number of points that the casing is held firmly against rattling under the vibration of the machine.

A particular embodiment of the invention appears in the accompanying drawing, in which

Fig. 1 shows in perspective a portion of the measuring mechanism of a heel-nailing machine with my improved abutment means and enclosing casing;

Fig. 2 is a detail, partly in elevation and partly in section, of one of the screws supporting both an abutment-lever and the casing; and

Fig. 3 is a sectional detail through the adjustable casing-support.

At 10 is shown a portion of the frame, together with the bracket upon which is mounted the measuring mechanism of the Glidden type of heel-attaching machine, to which reference has already been made. Resting directly upon the bracket is a bar 12, serving as a guide for the lowest of a vertical series of horizontally movable wedges 14. These wedges have formed upon their rear edges rack-teeth, with which mesh elongated pinions 16, 16. A double rack-bar 18 is arranged to reciprocate with slight clearance in a space in the under side of the bar 12. The rack-bar is acted upon by a spring (not shown), and engages both pinions and turns them oppositely, thereby causing the opposite travel of the wedges 14 in pairs. The upper wedge is attached to and elevates, under the influence of the spring transmitted through the gearing and series of wedges, a block 19 in which is secured a rod 20. This rod, in turn, swings the top lever of the heelng machine upon its fulcrum and lowers the jack to bring into engagement the shoe upon said jack and the heel which is to be nailed. The guide-bar 12 is secured to the frame-bracket by screws 22, which are subjected to various stresses tending to loosen them. They may thus be raised above the upper surface of the bar,

which is then free to move. To relieve the screws of the strains upon them, I fix the bar positively against this longitudinal movement. Projecting from the bracket, in proximity to each end of the bar, is a screw 24, about which is fulcrumed a lever 26. The upper extremity of the lever is forced against the bar by an adjusting screw 28, which is threaded through the lower arm of the lever and engages the frame. The bar is thus retained between rigid abutments, which may be caused to bear with all necessary pressure and entirely free the screws 22 of lateral strains, these screws now chiefly holding said bar against upward displacement. Under these conditions, the screws remain seated, and there is no interference between them and the lower wedge, nor between the guide-bar 12 and the rack-bar 18.

20 It is desired to protect the measuring mechanism from dirt, nails and other objects which might clog it. For this purpose, it is surrounded by a casing 30 resting against the frame and bracket and having an opening 32 at its top, through which passes the block 19. The bottom is also open to permit the application of the casing to the measuring mechanism. Other openings, as those indicated at 34, permit the inspection and lubrication of 30 the enclosed mechanism. It is desired that this casing shall be readily removable, and that it shall be held securely and so it does not rattle under the influence of the vibration of the machine in operation. I effect this, and 35 at the same time lessen the cost of the mounting, in the following manner: Each of the screws 24, upon which are fulcrumed the abutment-levers, has a head 36 provided with a circumferential groove, at the opposite sides 40 of which are inwardly converging walls 38, 38. Projecting downwardly within the casing are lugs 40, the ends of which are so located and so oppositely inclined at 42 that, when said casing is properly situated over the measuring mechanism, they engage the walls 38, and, seated by the weight of the casing, hold the lower portion firmly against movement. At 45 the top of the casing, in front of the opening 32, is a depression with upwardly converging walls 44, 44. Threaded into the front of the frame-bracket is a screw 46 arranged to clamp adjustably against rotation an eccentric-disk 48, the periphery of which is inclined at 50, 50 to correspond to the incline of the walls 44, 44. 50 The adjustment of the eccentric places its upper edge at different distances from the screws 24. It may be located at such an angle about its mounting screw that, when the lugs 40 are seated in the grooves in the screw-heads 36, the walls 44 and 50 are in like firm engagement. 55 There is thus afforded a three-point bearing, by which the casing is securely supported, and which calls for the employment of elements peculiar to the support at one only of the three points. Complete access to the enclosed

mechanism may be had by simply lifting the casing from its supports.

Having described my invention, what I claim as new and desire to secure by Letters Patent of the United States is:

1. In a shoe machine, mechanism having reciprocatory members arranged in a co-operating series, a guide for one of the members, and variable pressure means engaging an end of the guide. 70

2. In a shoe machine, measuring mechanism having reciprocatory members, a guide for one of the members, an abutment-lever engaging each end of the guide, and means for varying the pressure of the levers against the so guide. 75

3. In a shoe machine, measuring mechanism having reciprocatory wedges, a bar furnishing a guide for one of the wedges, and a lever contacting with each end of the bar. 85

4. In a fastening-inserting machine, a frame measuring mechanism mounted upon the frame and having a vertical series of reciprocatory wedges, a bar furnishing a guide for the lowest wedge, securing means extending through the bar, a lever fulcrumed upon the frame at each end of the bar and contacting therewith, and a screw threaded through each lever and engaging the frame. 90

5. The combination with a mechanism having a member fixed against movement, of a casing for the mechanism, mounting means for the casing, and retaining means for the fixed member carried by the mounting means. 95

6. The combination with a mechanism having a guide member, of an enclosing casing for the mechanism, supporting means for the casing, and retaining means for the guide member movable upon the supporting means. 100

7. In combination, the frame of a fastening-inserting machine, measuring mechanism mounted upon the frame, a member projecting from the frame adjacent to the measuring mechanism, a casing for the measuring mechanism mounted upon the member, and abutment means carried by the member and contacting with an element of the measuring mechanism. 105

8. In combination, the frame of a fastening-inserting machine, measuring mechanism mounted upon the frame and including a guide member, a screw threaded into the frame at each extremity of the guide member, a casing for the measuring mechanism supported by the screws, and an abutment member carried by each screw and contacting with the guide member. 115

9. In combination, the frame of a fastening-inserting machine, measuring mechanism mounted upon the frame and including a guide member, a screw threaded into the frame at each extremity of the guide member, a casing for the measuring mechanism supported by the screws, an abutment member carried by each screw and contacting with 125

130

the guide member, and a further support for the casing adjustable at its point of contact therewith toward and from the screws.

10. In combination, the frame of a fastening-inserting machine, measuring mechanism mounted upon the frame and including a guide member, a screw threaded into the frame at each extremity of the guide member, a casing for the measuring mechanism supported by the screws, a lever fulcrumed upon each screw and contacting with the guide member, and a screw threaded through each lever and engaging the frame.

11. In combination, the frame of a fastening-inserting machine, measuring mechanism mounted upon the frame and including a guide member, a screw threaded into the frame at each extremity of the guide member and provided with a slotted head, a casing for the measuring mechanism having projections entering the slots of the screw-heads, and a lever fulcrumed upon each screw and contacting with the guide member.

12. The combination with a frame and mechanism mounted thereon, of a casing for

the mechanism, supporting members for the casing fixed against movement upon the frame, and a supporting member for the casing adjustable upon the frame.

13. The combination with a frame and mechanism mounted thereon, of a casing enclosing the mechanism, two supporting members for the lower portion of the casing fixed against movement upon the frame, a third supporting member for the upper portion of the casing, and means for securing said third member with its point of engagement with the casing at different distances from the fixed members.

14. In a nailing machine, the combination with a machine-frame, of measuring mechanism mounted thereon, a casing enclosing the measuring mechanism, projections from the frame with which the casing contacts, and an eccentric adjustable upon the frame and contacting with the casing.

In testimony whereof I have signed my name to this specification.

THOMAS LUND.
